Claims priority, application Germany Jan. 5, 1961
19 Claims. (Cl. 103—161)

This invention relates to piston pumps.

The invention provides a piston pump comprising a rotary guide system and a cooperating rotary pumping system; said pumping system including a cylinder block, a pump body mounting said cylinder block for rotation about a first axis and providing in association therewith intake and delivery chambers extending about said rotary piston each over a major portion of a 180° arc centred on said first axis, and a reciprocating piston mounted in said cylinder block for movement to and fro along a path which is fixed with respect to said cylinder block and transverse to said axis; said guide system including a guide member which is rotatable about a second axis spaced from the first axis, and means coupling said systems whereby in operation to reciprocate said reciprocating piston along said path so as to draw fluid from the intake chamber and discharge it into the delivery chamber in each revolution of the cylinder block.

One drawback of known types of piston pumps in use with liquid is their limited suction head. Suction head is determined in part by atmospheric pressure, vapour pressure of the liquid, and the resistance of the pipe leading to the intake of the pump; nothing can be done about these factors. However further major factors determining the suction head of a pump are the length of intake passages wherein liquid is accelerated, the speed of operation and certain dimensions of the pump. The length of the intake passages cannot in known piston pumps be reduced indefinitely because of the need for a valve controlling intake.

The present invention avoids the need for a valve controlling intake and so enables a better suction head to be obtained than with a pump of known type under similar conditions. It also enables the pump to be dimensioned for further improvement of the suction head.

In one preferred embodiment of the invention, the guide member of the guiding system may be a guide member piston spaced axially from the cylinder block and the coupling means may be a reciprocating slide mounted in the guide member for movement to and fro along a path which is fixed with respect to the guide member and transverse to the second axis, and a coupler rigidly coupling the reciprocating members. This enables the guide system to function also as a pumping system, by the provision of intake and discharge chambers in association also with the second rotary piston.

If it is not desired to use the guiding system for pumping, the same disposition as mentioned in the preceding paragraph may be used, but without provision of intake and discharge chambers for the guide member, which becomes merely a convenient device to carry the reciprocating slide. In the case this slide may be a simple rectangular-section slide: this has constructional advantages that will be explained later.

In a pump according to the invention the pumping system may have several cylinder blocks, as may also the guiding system have several guide members, these cylinder blocks and guide members being arranged in spaced relation along the axes. The different pumping sections may be connected in series or in parallel.

The pump according to the invention is readily controllable to vary the output at constant speed: this can be done by reducing the stroke of the reciprocating pistons

2

of the pumping systems by reducing the spacing between first and second axes, or by displacing the intake and delivery chambers relative to those axes so that the reciprocating pistons discharge somewhat to the intake chamber.

5 The invention has two further valuable aspects: thus according to one aspect it provides a piston pump for liquids having at least three pumping sections and an intermediate container, said section including a stage delivering liquid to said container, a further stage taking liquid from the container and delivering it towards an outlet, and a leakage section taking liquid which has leaked from other parts of the pump and delivering it to the container. There is therefore no need to provide piston- or shaft-sealing means, because leakage is recirculated; this in turn reduces the power consumption of the pump for a given output and makes it easier to construct.

According to the second further aspect the invention provides a piston pump for liquids comprising at least two stages (called first and second stages), an intermediate container between the first and second stages, an intake from which (directly or indirectly) the first stage takes liquid, an outlet towards which (directly or indirectly) the second stage delivers liquid, and a pressure-relief valve connected between the outlet and the container and set to 20 a predetermined pressure whereby to deliver liquid from the outlet to the container when the outlet pressure exceeds the predetermined pressure. There is also, preferably, a pressure relief valve between the container and the intake.

25 The features of the last two paragraphs can conveniently be combined: a further preferred feature is a capillary tube leading into a leakage-collecting zone from a high point in the container to remove air which may be pumped thereto, the capillary tube presenting a small resistance to 30 air but a large resistance to liquid.

35 The features of the last three paragraphs are advantageously combined with those mentioned earlier in a triple section pump, having a first rotary system acting as a guide system and a second rotary system which exhibits a cylinder block having three sections and wherein 40 are guided three reciprocating pistons. The first rotor section of said triple section pump is a main pumping section. The medium to be conveyed is pumped into an intermediate tank from this section. From the latter it is conveyed into the delivery pipe by a second pumping section which acts as a dosing or metering pump section. The third pumping section serves as a leakage pump. The liquid pumped leaks out between the reciprocating pistons and their bores; this leakage is channelled to the suction pipe of said third pumping section and is returned directly 45 into the intermediate tank.

50 Various embodiments of the invention will now be described by way of example with reference to the accompanying diagrammatic drawings, in which:

55 FIGS. 1a to 1d are diagrammatic plan views of a piston pump according to the invention illustrating the two rotary systems thereof in different positions;

60 FIGS. 1e and 1f are diagrams illustrating the motion of a coupler forming part of the pump of FIGS. 1a to 1d;

65 FIGS. 2a to 2d are views similar to FIGS. 1a to 1d of a modified form of pump;

70 FIG. 3 is a partially sectioned perspective illustration of a further form of piston pump showing the relative disposition of the two rotary systems;

65 FIG. 4 is a sectional perspective view of another piston pump according to the invention, comprising two rotary systems, one system with guide members and one system with cylinder blocks, the pumping system including three reciprocating pistons;

70 FIG. 5 is a perspective illustration of parts of yet another pump wherein the drive is provided through a coupler and not through a rotary piston;

FIG. 6 is a perspective view showing parts of a composite pump according to the invention made up of two component pumps each with two rotary systems acting as pumping systems; the guide members and cylinder blocks and the casing (shown in part only) are depicted drawn apart;

FIG. 7 is a perspective view of a coupler coupling two reciprocating pistons, as may be employed in pumps according to the invention;

FIGS. 7a, 7b and 7c show in partial perspective different forms of couplers;

FIG. 8 is a section through a pump according to the invention in which the throughput may be varied;

FIG. 9 is a sectional view of a pump which shows another arrangement for the continuous variation of the throughput;

FIG. 10 is a section along the line X—X in FIG. 9;

FIGS. 11a and 11b are partial perspective views which show dispositions for the sealing and lubrication of a guide member or cylinder block in a pump according to the invention;

FIG. 12 is a sectioned perspective illustration which diagrammatically shows parts of a pump according to the invention having three pump pistons;

FIG. 13 is a longitudinal section of a practical form of construction of the pump diagrammatically illustrated in FIG. 12;

FIG. 14 is a sectional view along line XIV—XIV in FIG. 13;

FIG. 15 is a section through a pressure relief valve forming part of the pump illustrated in FIGS. 13 and 14 (this section is taken in a plane different from the section planes of FIGS. 13 and 14);

FIG. 16 is a diagram showing the relative positions of the rotary systems in the pump of FIGS. 13 to 15 and showing also section lines XIII—XIII and XIV—XIV (the eccentricity of the centres of axes of the guide members and cylinder blocks is shown exaggerated);

FIG. 17 is a flow chart for the pump system illustrated in FIGS. 12 to 16;

FIG. 18 is a partially sectioned "exploded" perspective view of a further form of pump wherein the positive coupling of two rotary systems is provided by means of flat sliders;

FIG. 19 is a section through a pump incorporating a rotary system as illustrated in FIG. 18;

FIGS. 20a to 20d show different forms of reciprocating pistons for use in pumps according to the invention, FIGS. 20a and 20d being perspective views of two different pistons and FIGS. 20b and 20c being longitudinal section and plan of a further form of piston;

FIG. 21 is a longitudinal section of a further practical embodiment of a pump according to the invention;

FIG. 22 is a section along line XXI—XXI in FIG. 23;

FIG. 23 is a section along line XXIII—XXIII in FIG. 21;

FIG. 24 is a section along line XXIV—XXIV in FIG. 21;

FIG. 25 is a section along line XXV—XXV in FIG. 21, and

FIG. 26 shows in perspective view a first rotary system and a reciprocating piston of a second rotary system, forming part of the pump illustrated in FIGS. 21 to 25.

The operation of one preferred embodiment of the invention will first be described with reference to the diagrams of FIGURES 1a to 1f; it is intended that this description should make it easier to understand the more detailed embodiments which are described later.

FIGURES 1a to 1d show a pump with its working parts in four different positions. The pump comprises two rotary systems comprising a cylinder block 1 and guide member 11 respectively formed with a diametral through-bore 5, and guide track 15 respectively containing reciprocating members in the form of a piston 2, and a guide element or slide 12 respectively which are slidable

to and fro along the bore and track respectively. FIGURES 1a to 1d each show two superimposed sections, one through the central planes of the cylinder block 1 and guide member 11 at right angles to the axes of rotation thereof. The pump includes a pump body but for clarity of illustration this body is illustrated only by the wall parts 3, 3' and 13 and 13' a pair for each rotary system, which divide intake and outlet chambers from each other.

One rotary system is indicated by full lines, whereas the other system is drawn in dotted lines. The cylinder block 1 of the first system has the form of a hollow cylinder rotating about the axis and being driven in the direction of the arrow 4.

The second rotary system is shown in dotted lines and is disposed beneath or above the first system; the guide member 11 of the second system rotates about the axis of rotation 10 and is driven in the direction of the arrow 14.

The reciprocating members 2, 12 are rigidly interconnected by means of a coupler 6 in the form of a square section rod received in square holes in the reciprocating pistons; thus the piston and slide perform a positively coupled motion wherein the reciprocating member of the one system possesses only one translatory degree of freedom or mobility relative to the other system, enabling it to perform a reciprocating motion in the bore of the cylinder block or guide member within which it is guided. In the example illustrated, the reciprocating members are arranged at 90° relative to each other. Though this angle of 90° will commonly be preferred in principle however the reciprocating members may be disposed at other angles to one another.

Assuming that FIGURE 1a shows the parts of the pump in a datum position, FIGURES 1b, 1c and 1d show these parts displaced by 45°, 90° and 135° respectively from the datum. The 180° displaced position corresponds to that of FIGURE 1a, while the positions wherein the parts are displaced by 225°, 270° and 315° correspond to FIGURES 1b, 1c and 1d respectively.

FIGURES 1e and 1f illustrate the motion of the coupler: FIGURE 1e shows the geometry of the arrangement and FIGURE 1f is a vector diagram. The coupler axis C moves about the imaginary axis D halfway between the axes of rotation 0 and 10 of the two systems, which turn at identical angular velocity W_0 . The coupler axis C moves on a circular cylinder having a diameter equal to the distance between the axes 0, 10, and its motion may be interpreted as a superimposed motion about the axes of rotation 0 and 10. The velocities of the motions about the axis of rotation 0 and 10, v_A and v_B may accordingly be added vectorially, in order to describe the velocity V of the coupler about the axis D. As will be understood from the drawing, this velocity V is constant and the motion of the coupler is therefore uniform.

It is possible, therefore, to operate the pump by driving the coupler with its axis travelling on a circular cylinder of diameter e : the coupler must however be so disposed as to be rotatable about its axis C. It will however generally be preferred, for constructional considerations, to supply the drive to one of the two rotary systems, e.g. either the cylinder block 1 or guide member 11. As will be seen from FIGURES 1a to 1f the perpendicular distance between the two axes of rotation 0, 10 corresponds to half the length of a stroke of the pistons and slide 12. A motion through 360° of the central axis of the coupler then corresponds to a rotation of both systems through 180°.

The coupler 6 is in each instance disposed centrally in both the piston 2 and slide 12.

In the diagrammatically illustrated pump of FIGURES 1a to 1d both rotary systems may be utilised as pumping systems; one system, the first system for example, may however act solely as a guide system and the second system alone may act as a pumping system.

As apparent from FIGURES 1a to 1d, when both sys-

tems are utilised as pumping systems, the delivery side for the first system including the cylinder block 1 is located on the right-hand side (as seen in the drawing) of the plane of symmetry passing through the housing parts 3 and 3', and the suction side is accordingly located to the left thereof. The reverse applies for the second system having the guide member 11; this system delivers towards the left-hand side as shown in the drawing.

One of the main advantages of the pump described lies in the fact that, in the or each rotary system a single reciprocating member exerts suction on one side as well as pressure on the other side, through an angular range of almost 180°. When one extremity of a reciprocating member—at the end of the pressure stroke—reaches the dead centre at which the extremity of the reciprocating member comes closest to the periphery of the corresponding cylinder block or guide member, it is carried along through a very short distance past the housing portion 3 or 13' separating the suction side from the delivery side, and then immediately starts on the suction stroke, whereas the other extremity of the same reciprocating member simultaneously starts on the delivery stroke again. Valves as in known piston pumps, or valve control gear, are thereby rendered superfluous.

The cylinder block 1, and guide member 11 are formed with a central cylindrical opening dimensioned so that firstly the reciprocating piston 2 and slide 12 are adequately guided during their entire reciprocating motion, secondly that a sufficiently pressure-tight seal is assured relative to the inner spaces of the hollow cylinders, and thirdly that the required space is available for the travel of the coupler 6.

FIGURE 2 illustrates a disposition similar to FIGURE 1. The difference between these dispositions resides in that the guide member 11 drawn in dotted lines possesses a greater diameter than the cylinder block indicated by full lines. The same reference numerals as in FIGURE 1 have therefore been utilised throughout, and no further description will be required.

The advantage of the FIGURE 2 pump is that the housing which is required to guide the cylinder block 1 and guide member 11 may easily be produced by fitting an excentric ring serving as a guide for the block 1 into the top and/or bottom of a simple cylindrical casing co-operating with the guide member 11 having the greater diameter.

FIGURE 3 shows a perspective illustration of a further form of pump according to the invention, having a first rotary system comprising two shafts 21 and 21' mounted in fixed bearings (not illustrated) so as to be rotatable about the same axis of rotation 20; one or other of these shafts may be driven by means (not shown) or both shafts may be driven synchronously. These two shafts 21 and 21' correspond in principle to the guide member 11 illustrated in FIGURES 1 and 2, but function merely to guide a pair of slides 22 and 22' movable along transverse slots 25 and 25' formed in the opposed extremities of the shafts 21 and 21'. The second rotary system comprises a cylinder block 31 rotatable about the axis 30; the block 31 is shown in perspective section so as more clearly to illustrate a diametrical bore 35 wherein a reciprocating piston 32 is slidably mounted. The slides 22 and 22' are rigidly coupled to the reciprocating piston 32 by means of a coupler 26. The housing 33 wherein rotates the cylinder block 31 is indicated only diagrammatically, and the required inlet and outlet chambers in the housing are not illustrated.

FIGURE 3 approximately corresponds to the position indicated in FIGURES 1c and 2c. In this position, the axis of the coupler 26 coincides with the axis of rotation 30 of the rotary piston 31. The piston 32 accordingly occupies its middle position in the bore 35. As a consequence of the excentricity of the two rotary systems, having axes 20 and 30, the coupler moves about an axis positioned between these axes in the same manner as that

shown in FIGURES 1 and 2, and the piston 32 is caused to travel back and forth in the bore 35 as shown in FIGURES 1 and 2.

The FIGURE 3 pump may be modified by replacing the block 31 by a cylinder block having several bores and disposed in a housing constructed accordingly. These bores then contain a corresponding number of reciprocating pistons which are all interconnected rigidly by means of the coupler. A pump of this type can be utilised as a multi-section pump, as will hereinafter be set forth in greater detail.

The guide system illustrated in FIGURE 3 comprises two partial systems disposed on either side of the pumping system along the direction of the axes of rotation. A two-part type of construction of this kind is necessary, in order to locate the coupler 26 symmetrically, so that a torque may be transmitted to the cylinder block 31 without the occurrence of forces which could cause the pistons to seize in their bores.

FIGURE 4 is a perspective section of a pump following the principles of FIGURE 2 wherein both rotary systems exhibit reciprocating pistons and slides guided respectively in a cylinder block and guide member, the section line being taken along a line corresponding to the line IV—IV of FIGURE 2c. The first of the two rotary systems comprises a pair of similar spaced guide members 41, 41' which correspond to guide member 11 indicated in dotted outline in FIGURE 2c and have an axis of rotation 40 which corresponds to the axis 10 in FIGURE 2c. The second rotary system comprises a cylinder block 51 located between the guide members 41, 41' and having an axis 50 which corresponds to the axis of rotation 0 of the rotary piston 1 in FIGURE 2c. Drive is supplied to the guide member 41 through a plate 46 attached thereto by means of bolts 47 and carrying a stub shaft 48 which may be coupled to a motor for example by a universal joint. Alternatively a direct drive or belt or other drive could be used. The cylinder block 51 possesses three bores 55a, 55b and 55c, whereof the axes lie in one plane (the section plane as illustrated in FIGURE 4). Pistons 52a, 52b, 52c are slidably mounted in the bores and rigidly connected by a coupler 49 with slides 42, 42' slidable in parallel tracks in the guide members 41, 41'. (The coupler 49 and the reciprocating pistons 52a, 52b and 52c are sectioned. The cylinder block 51 is sectioned through its central plane, whereas the guide member 41 is sectioned along a plane which is parallel and excentric to its central plane, as apparent from FIGURE 2c. Beyond its section plane, the reciprocating slide 42 is shown in dotted lines in order clearly to show its position relative to the reciprocating pistons 52a, 52b, 52c.)

In the position shown in FIGURE 4, and as also apparent from FIGURE 2c, the central axis of the coupler 49 coincides with the axis of rotation 50 of the cylinder block 51.

When the plate 46 is driven in the direction of the arrow 44 the guide member 41 turns in the bore 56 of the housing 57, which is indicated in dotted lines. (Suction and delivery chambers of the housing 57 are not shown in the drawing.) As a consequence of the rigid connection between the reciprocating slide 42 and the reciprocating pistons 52a, 52b, 52c by the coupler 49, a rotation of the guide member 41 causes a rotation of the cylinder block 51 in the bore 58 of the housing 57 which is excentric to the bore 56.

The central axis of the coupler 49 rotates about an axis disposed between the two axes of rotation 40 and 50, as already described in detail in connection with FIGURES 1 and 2.

The FIGURE 4 pump has a first rotary system which may be utilised both as a guide system and as a pumping system. The three reciprocating pistons 52a, 52b, 52c of the second rotary system oscillate together and provide a separate three part pumping system and these parts may be connected in parallel or in series as desired, by

an appropriate disposition of external pipes. It is thus possible for example to utilise the pump illustrated as a triple-stage pump. All three partial systems may however also be connected in parallel, or two may be connected in parallel and connected in series with the third. One form of multi-section pump of this nature will be described later in more detail.

In the FIGURE 4 pump the first rotary system comprises two similar guide members 41, 41' disposed on either side of cylinder block 51, as in the FIGURE 3 pump, and the guide member 41 is driven. As diagrammatically shown in exploded view in FIGURE 5 the pump may however alternately be driven through the coupler here designated 49'. The coupler 49' has its extremities formed as pivot bearings 49a and 49b mounted in bores 49a' and 49b' formed in the end faces of interconnected coaxial shafts 48a, 48b, these bores being eccentrically positioned relative to the common axis of rotation a of the rotary shafts. The coupler 49' revolves about the axis a and in doing so, the axis of the coupler travels along a circular cylinder 53 whereof the diameter D is equal to the eccentricity of the axes of rotation 40' and 50' about which revolve the cylinder block and guide members (not shown) of the two rotary systems wherein are guided the reciprocating members 42 and 52. A drive through the coupler is only a practical proposition for large eccentricities.

FIG. 6 shows a composite pump made up of two associated component pumps. Each component pump comprises, as in previous embodiments, two rotary systems interlinked by a coupler: the coupler, designated 66, is common to both component pumps.

The first component pump comprises a first rotary system having two guide members 61a, 61b rotatable about a common axis 60, and formed with diametral tracks the axes of which are coplanar and which locate reciprocating slides 62a, 62b. The second rotary system of the first component pump includes a cylinder block 71 rotatable about an axis 70 parallel to but spaced from the axis 60: the block 71 is formed with a diametral bore which has an axis at right angles to that of the bores of the first system.

The second component pump includes a first rotary system having two guide members 61a', 61b' rotatable about a common axis 60' and formed with diametral tracks the axes of which are coplanar and locate reciprocating slides 62a', 62b'. The second rotary system of the second component pump comprises a cylinder block 71' rotatable about an axis 70' parallel to but spaced from the axis 60'.

The guide members 61b, 61b' are integral with one another and with a gear ring 69 arranged between them, and this gear ring is driven by a pinion 68: the axes 60 and 60' accordingly coincide in space. The axes of the tracks in the pistons 61b, 61b' are however axially displaced by 45°, and it is to be noted that the axes 70, 70' do not coincide.

The coupler 66 extends through square holes in the reciprocating slides 62a, 62b, 62a', 62b', and pistons 72, 72', and couples the rotary systems for rotation together on application of driving torque to the pinion 68: the motion of the various parts will be understood from the previous description.

The guide members 61a, 61b, 61a', 61b', and cylinder blocks 71, 71' are located in annular recesses or guideways 75a, 75b, 75a', 75b', 85, 85' respectively formed in the housing. Each guide member and piston acts as an elementary pump. Intake and delivery chambers are associated with each recess: chambers 76, 76', 86, 86' are shown for the guideways 75a, 75a', 85, 85', while chamber 76b serves for both guideways 75b and 75b' for reasons to be explained. Webs 77 separating intake and delivery chambers are shown, these webs corresponding to the parts designated 3 and 13 in FIGS. 1 and 2.

Considering a simple cylinder block, the motion of the reciprocating piston therein is sinusoidal and the pressure in the delivery chamber will therefore rise to a maximum at the middle of the delivery stroke. By connecting two component pumps phase-displaced by 45°, so that the peak pressures of one coincide with minimum pressures of the other, a smoother delivery and total pressure is obtained. The connections between the various delivery chambers may be by external piping: 10 for the guide members 61b, 61b' the common chamber 76b performs an equivalent function.

For reasons of convenient illustration, the parts of the FIG. 6 composite pump are "exploded" axially as well as radially: the resulting lands of axial length L 15 which are seen in the housing are not constructionally necessary and in a practical construction may be omitted.

FIGURES 7, 7a, 7b and 7c show practical examples of couplers by means of which the reciprocating pistons of previously described pumps may be rigidly interconnected. FIGURE 7 illustrates two reciprocating members 91 and 92 extending at 90° to each other and rigidly interconnected by means of the coupler 93. The coupler 93 comprises two rectangular-section bars 94a and 94b between which is disposed a rubber insert 95. 25 This assures a tight fit of the coupler in the square section holes of the reciprocating pistons. This construction of the coupler moreover offers the advantage, that the square section holes in a piston or slide need not be machined to so high a degree of accuracy as 30 would have to be the case if the couplers were made in the form of a solid metal rod. FIGURE 7a shows a further form of construction of the coupler, a wavy sheet 96 of springy material being disposed between the two bars in FIGURE 7a. FIGURE 7b shows a coupler 35 whereof the insert consists of a resilient synthetic material 97. FIGURE 7c shows a coupler composed of laminated sheets or blades alternately composed of different materials, e.g. metal, resilient plastics, etc., or alternatively of identical materials (or materials of 40 analogous nature).

As already stated initially, the delivery performance of a pump according to the invention may be varied by varying the distance separating the axes of rotation of the two rotary systems, the stroke of the reciprocating pistons and slides being thereby also varied. FIGURE 8 shows a vertical section through a mechanism designed for this purpose, the section plane being such as to contain the two axes of rotation. The first rotary system comprises two guide members 101 and 101' which 45 rotate about the axis 100, and two reciprocating slides 102 and 102' which are guided in the tracks of these guide members. The guide member 101 is driven by means of the shaft 108 and a driving dog 107. The guide members 101 and 101' are guided in two cylindrical bores 109 and 109' of a housing 120, the first rotary system being arranged as a pure guiding system. The second rotary system comprises a cylinder block 111 and a reciprocating piston 112 which is guided in the bore 115 thereof. The cylinder block 111 is mounted in a guide housing 121 which in turn is mounted in a recess 122 of the housing 120 for movement in one direction in the plane of the paper and at right angles to the axes of rotation. The guide housing 121 is disposed so that the cylinder block 111 turns about an axis of rotation 110 which is eccentric relative to the axis of rotation 100. If the guide housing is now displaced within the recess 122 of the housing 120 in the direction specified, the distance between the two eccentric axes of rotation 110 and 100 is varied accordingly and thus also the stroke of the reciprocating piston 112. Displacement of the guide housing 121 is carried out by means of a threaded spindle 123 articulated to the guide housing 121, and extending through a threaded hole in the wall of the housing 120: the spindle may 55 be screwed in or out by means of a handle 124. A com-

pression spring 125 disposed opposite the spindle between the guide housing 121 and the corresponding side of the housing 120 continuously urges the guide housing towards the right in the direction of the arrow 126. As already mentioned, the first rotary, or guiding, system is disposed on either side of the second, or pumping, system. The reciprocating slides 102 and 102' of the guiding system are rigidly connected to the reciprocating pistons 112 of the pumping system by means of the coupler 106, the piston and slides of the two systems being dephased by 90° relative to each other. The chambers 127, 128 in the guide housing 121 for the suction and delivery respectively are indicated in dotted lines.

FIGURES 9 and 10 illustrate a mechanism by means of which the spacing between the axes of rotation of the two rotary systems in a pump according to the invention may be varied, as well as the position of the plane defined by the axes of rotation relative to the housing of the pump.

FIGURE 9 shows one half of the mechanism in longitudinal section, while FIGURE 10 is a section taken along line X—X in FIGURE 9. The first rotary system, which is arranged as a guiding system, is driven by means of a shaft 351 rotatably mounted about a fixed axis 350 through a driving dog 352: this first system has a guide member 353 and a reciprocating slide 354 guided in a track thereof. The guide member 353 is mounted in an eccentric ring 355 which is integral with a gear ring 356. The eccentric ring is embraced by an inner housing 357 wherein is mounted the cylinder block 358 of the second rotary system. The intake and discharge chambers 361 and 362 respectively for the liquid to be pumped are disposed in the housing 357 but since the section plane of FIGURE 9 passes through the partitions 363 separating the chambers from each other, the chambers are not visible in that figure. If the ring gear 356 is moved angularly by the rack 364 shown (FIGURE 10) this not only varies the spacing between the two axes of rotation 350 and 360 of the guide member 353 and cylinder block 358 thereby securing a variation in length of stroke, but also the position of the plane defined by the two axes of rotation 350 and 360, relative to the section plane of FIGURE 9, thereby varying the delivery.

The guide member and cylinder block are mounted in the housing bores in a close fit to ensure that the clearance between the housing and the guide member and cylinder block is small enough to ensure a satisfactory seal; the clearance must not be so small however as to hinder ready movement of the guide member or cylinder block.

FIGS. 11a and 11b show two ways of lubricating and sealing a guide member or cylinder block in its housing, in a pump according to the invention: FIG. 11a shows only, as an example, a cylinder block 133 and the immediately adjacent part of the housing 134, while FIG. 11b shows only a part of a housing designated 134'.

Referring to FIG. 11a, the cylinder block 133 is formed adjacent its end faces with peripheral grooves 139: longitudinal grooves 131 lead from the grooves 130 to the end faces. Grooves 131 are fed with lubricant by any known means. Additional peripheral grooves 136 are formed in the piston 133 on the side of the grooves 130 away from the end faces and close to the bore 135 therein. Suction and delivery chambers 138, 137 are so formed in the housing 134 that the suction chamber overlaps the grooves 136 while the delivery chamber extends longitudinally by a length corresponding only to the bore 135. Thus fluid escaping longitudinally of the block 133 on the delivery side thereof reaches the grooves 136 whereby it is returned to the suction side.

FIG. 11b shows a similar arrangement differing from that of FIG. 11a only in that the grooves are formed in the housing and not in the block.

The grooves 130 could be helical.

FIGURES 12 to 16 illustrate a further form of pump according to the invention having three pumping sections: FIGURE 17 is a flow diagram or chart showing the operation of this pump.

The three-section pump of FIGURES 12 to 17 comprises a first rotary system operating as a pure guiding system. This guiding system comprises two guide members 210 and 219 which are mounted and guided in cylindrical rings 209 and 218 for rotation about the axis 251. The cylindrical rings 209 and 218 are press-fitted into the extremities of a bore in the housing part 202. The cylinder block 204 of a second rotary system forming the pump system is mounted for rotation about an axis 252 in a sleeve 203 which is also press-fitted into the bore in the housing part 202, the sleeve 203 being eccentric to the bore and spacing apart the rings 209, 218. The sleeve 203 has slots 255, 256 and 257 providing delivery chambers and slots 265, 266 and 267 providing suction chambers. The cylinder block 204 has three parallel diametral bores mounting reciprocating pistons 205, 206, 207 providing the three pumping sections referred to. The guide members 210, 219 of the guiding system have diametral bores mounting reciprocating slides 211, 220. The slides 211, 220, and pistons 205, 206, 207 are rigidly interconnected by a coupler 208 which maintains the axes of slides 211, 220 in the same plane and at right angles to the plane of the pistons 205, 206, 207.

The drive to the two rotary systems is provided through the guide member 210 in the manner set forth in connection with FIGURE 4: that is, the guide member 210 is coupled to a plate 214 by means of pins 212 and coil springs 213, the plate 214 being coaxial with the guide member 210 and having a central bore into which projects a shaft 216 whereof the extremity is forked. A rod 215 extending through the plate 214 is engaged by the forked extremity of the shaft 216. The shaft 216 may be directly driven by an electric motor, or through a universal joint, or by means of a transmission gear or other driving system.

All rotating parts are enclosed in the bore of the housing part 202 in the manner best illustrated in FIGURES 13 and 14; a housing part 201 is secured to the top of part 202, a seal or packing 217 being disposed between the contact faces of the two housing parts. The housing part 201 has a peripheral flange 201a extending longitudinally towards the part 202, and the end face of the flange is formed with an annular groove 201b. A housing part 204 in the general form of a stepped tube has its larger end flanged at 204a and received in the groove 201b: the smaller end of the part 204 embraces a radial flange on the housing part 202 and is sealed thereto by an O-ring 223. A further housing part 227 in the form of a tube with an inturned annular wall 227a at one end engages with its opposite end a sealing ring 233 which is inserted in the groove 201b. The end wall 227a is clamped to a coaxial tubular extension 202a of the part 202 by means of an end closure 229; thus the housing part 227 exerts endwise pressure against the sealing ring 233 to hold the ring and the part 224 in position. Housing parts 202, 201 and 224 define an intermediate container or space 269, while parts 224, 227 define an outer container or space 268 wherein is mounted a filter 225, the filter being clamped between these two housing parts.

The guide members and slides and cylinder blocks and reciprocating pistons operate as described in connection with previous figures. The sleeve 203 wherein the suction and delivery chambers are formed must occupy a definite position relative to the plane defined by the axes of rotation 251, 252 of the two rotary systems. As apparent from comparison with FIGURES 1 and 2, the maximum pumping effect is attained for a given spacing between the axes of rotation 251, 252 of the two rotary systems, if the partitions separating the delivery chambers 255, 256, 257 from the suction chambers 265, 266,

267 lie in this plane. If there is no need to vary the pumping effect, the sleeve 203 is fixed relative to the housing part 202, which comprises the intake pipes 283, 234 and 287, and delivery pipes 275, 276 and 235, so that the suction and delivery chambers are in communication over their full peripheral extent with the corresponding delivery pipes.

When the sleeve 203 is so turned, that the delivery chambers are in communication over only a part of their peripheral extent with the corresponding delivery pipes and are in communication over the remaining part of their peripheral extent with the corresponding suction pipes (the reverse applying to the suction chamber), then the delivery volume is reduced since suction is also exerted on the delivery side on the one hand, and pressure is also exerted on the suction side on the other. As may easily be appreciated, the delivery will be equal to zero when the sleeve 203 is so turned, that half the suction and delivery chambers in each case are in communication with the suction as well as delivery pipes in the housing part 202.

The operation of the pump illustrated in FIGURES 12 to 16 will now be described with reference also to FIGURE 17.

The liquid conveyed is supplied to a suction pipe 232 which is secured to the side of the housing part 227 by means of a nut 230 and a packing 231. The fluid flowing in through the suction pipe 232 is drawn through the filter 225 disposed in the space 268, and thence, by means of the reciprocating piston 205, through the suction passage 285 and the chamber 265. The reciprocating piston 205 forces the fluid on the other side through the chamber 255 and the delivery pipe 275 into the intermediate container 269. From the intermediate tank, the liquid is drawn through the suction pipe 234 and the suction chamber 266 by the piston 206 of the dosing or metering pump section—the main section—and is forced through the chamber 256 into the delivery pipe 276. If the pump is utilised in an oil burner for example, the delivery pipe 276 leads to the atomising nozzle, or if it is utilised as a petrol injection pump, to the engine. In order to limit the pressure in the delivery pipe, a branch pipe 270 leads from the delivery pipe through a pressure limitation valve 271, which latter is shown in FIGURE 15 as a ball valve comprising a valve seat 245, a ball 244 and a compression spring 243 urging the ball against the seat. From the pressure limitation valve, a pipe 275 leads back to the intermediate container 269. The maximum pressure in the delivery pipe may thus be limited; adjustment is provided for by a screw 246 controlling the amount of compression of the spring.

The pressure in the intermediate container 269 is also limited; for this purpose a pressure limitation valve 249 is provided which is so connected to the intermediate container through a pipe 279 on the one hand and to the suction pipe 285 of the main pump section on the other, that when a pressure exceeding a given maximum occurs in the intermediate container 269, the valve is opened and connects the container to the suction pipe. The valve may be of known type: FIGURE 14 shows a ball valve controlled by means of a compression spring.

The third section (to be called the leakage section) of the pump shown in FIGURES 12 to 17 serves the purpose of pumping back to the intermediate container 269 such liquid as leaks into the interior of the cylinder block 204 past the reciprocating pistons 205, 206 and 207. The leaked liquid rises in the central space wherein the coupler 208 moves until it reaches a collector space 280 the bottom of which is formed with a trough 281. From the collector space 280, the leaked liquid is drawn through a suction pipe 287 connected to the trough 281 and through the suction chamber 267 by the action of the reciprocating piston 207; this liquid is then forced back into the intermediate container 269 through the delivery chamber 257 and the delivery pipe 235.

The intermediate container 269 is connected to the collector space 280 by means of a capillary tube 237: the delivery pipe 235 and the capillary tube 237 open into the highest point of the intermediate tank 269. The capillary tube operates as follows: when the collector space 280 is empty or partly empty, as will mostly be the case, air or a mixture of air and liquid is pumped into the intermediate container by the leakage section of the pump. This air is returned into the collector space through the capillary tube 237. The capillary tube opposes slight resistance to the throughflow of air and a high resistance to the throughflow of liquid. The "position" of the capillary will appropriately be so selected, that it just allows passage to the volume of air which can, as a maximum, be pumped into the intermediate container by the leakage pump section.

The three-section pump shown in FIGURES 12 to 17 is preferably utilised as a petrol injection pump or as an oil injection pump for atomising burners. Apart from the advantage of a simple and compact form of construction, the device also possesses the additional advantage, that it may be operated with a single suction pipe and a single delivery pipe. In previously known systems, it was necessary to provide a return pipe to the main tank, since a second pump was otherwise required to remove excess of fluid conveyed and also gas or air bubbles from the system.

FIGURES 18 and 19 illustrate parts of a further form of pump having features in common with that of FIGURES 12 to 17. FIGURE 18 shows the rotary parts diagrammatically in partially sectioned "exploded" perspective view, the individual parts being shown drawn apart to enhance clarity. FIGURE 19 shows a section through the pump illustrated in FIGURE 18 which in respect of position corresponds to the FIGURE 13 section, the rotary parts however being turned through 90° in comparison with the section illustrated in FIGURE 13. Parts shown in FIGURES 18 and 19 which correspond to parts described with reference to FIGURES 12 to 17 are given the same reference numerals and will need no further description.

In the pump shown in FIGURES 12 to 17, both first rotary systems comprise cylindrical reciprocating pistons or slides which are connected to each other by means of a coupler in the form of a prismatic rod so that torque may be transmitted from the reciprocating slides of the one system to the reciprocating pistons of the other system. For this purpose square-section holes are required in the cylindrical reciprocating pistons and slides: however such holes are not readily made by mass production methods bearing in mind that they need to be accurate enough to eliminate play between the coupler and the pistons and slides; the pump not operating properly unless this is the case. To facilitate production and reduce expense, in the construction of FIGURES 18 and 19 flat "sliders" 310, 310a and 311 are employed. These flat sliders, which are preferably made of simple sheet or plate material can readily be formed with accurate square holes 312 in simple manner by means of an appropriate punch and die. The sliders 310 and 310a are sliding fit in grooves 313 and 313a in rotary guide members 210' and 219' and can freely reciprocate in these grooves in radial direction: the guide members 210', 219' correspond in function to the guide members 210, 219 of FIGURES 12 to 17, while the slides 310, 310a correspond in function to the slide pistons 211, 220 of these figures. The slide 311 is a sliding fit in a similar radial groove 314 located in an end face of the cylinder block 204 and is thus able to transmit thereto the torque exerted thereon by means of the coupler 208. The pump pistons 205 to 207 have cylindrical bores 315, 316, 317 through which the coupler passes. The diameter of the bores is such that the edges of the coupler 208 are in contact with the sides of the bores; thus the coupler does not transmit any torque to the pump pistons 205, 206

and 207 and torque transmission thereto occurs only by reason of the slides. However the coupler is able to cause an accurate translatory displacement of the pistons 205, 206 and 207 in the bores 265, 266 and 267. In order to prevent the fit of the coupler in the cylindrical bores of the pump pistons from worsening with time, the coupler may be constructed in the form of a square-section rod with its edges rounded off, so that they are in contact over a greater area with the sides of the bores 315, 316 and 317.

The grooves wherein reciprocate the flat slides 310, 310a and 311, are preferably milled into the end faces of the guide members 210, 219 and cylinder block 204. The flat slides are thereby guided on three sides.

On the fourth side, the slides 310a and 311 are guided by means of the immediately adjacent cylinder block 204, and the guide member 210 respectively. For the flat slider 310, guidance at the fourth side is provided by a cover plate 318, which is pressed on to the guide member 210 by means of helical springs 319. The drivers 212 which transmit the driving couple from the shaft 216 to the guide member 210 of the guiding system, are passed through holes 319 located in the cover plate 318 and are inserted into holes 319a in the guide member 210.

As will be appreciated, the coupler 208 is a close fit in the openings of the slides 310, 310a, 311 and is a close fit also in the cylindrical bores of the pump pistons; the coupler may if necessary be secured against axial displacement in known manner.

In certain cases it may be desirable to fit flat slides in the guiding system only. In this case the median portions of the pump pistons may be made flat, so that the punching out of square openings does not present any difficulties. Examples of this nature are illustrated in FIGURES 20a to 20c.

The reciprocating piston illustrated in FIGURE 20a possesses two cylindrical piston extremities 320 and 321, which are interconnected by means of a flat part 322, made of plate material for example. A square hole 323 is punched out of the flat part. This construction of the reciprocating piston is especially advantageous if the two cylindrical parts 320 and 321 consist of synthetic material moulded about the plate part 322; in such case the plate part 322 extends somewhat into the parts 320 and 321.

FIGURES 20b and 20c show in section and plan view respectively a piston 324 wherein are milled two slots 325 and 326 in the manner illustrated. In this case it is also possible to punch a polygonal hole 327 out of the narrow central bridge piece remaining between the milled slots 325 and 326 by means of simple tools.

FIGURE 20d illustrates a further possibility. In this example a square-section slot 328 is milled into the reciprocating piston 329 from one side. The coupler inserted into this slot must be rigidly connected to the reciprocating piston e.g. by soldering or brazing.

FIGURES 21 to 26 show another embodiment of the invention.

Parts which are similar to those already described with reference to other embodiments are again given the same reference numerals. The first rotary system which in this case is arranged purely as a guiding system, comprises a shackle 185 which is centrally connected to the extremity of a driving shaft 186 by means of a screw 187.

The two arms 185a and 185b of the shackle 185 are connected by means of a cylindrical pin 187 secured thereto by means of a screw 187a which is screwed into a threaded hole in the arm 185a. The pin 187 extends through a central transverse bore in the middle portion 189 of a cylindrical reciprocating piston 188 which portion is of larger diameter than the ends of the piston. The reciprocating piston 188 forms part of the second cylinder block comprising also a rotary piston 190 mounted in a cylindrical housing 191. The cylindrical housing 191 is held in a shell 192a and 192b and is rotatably guided therein as will be described. The housing 191 has a suc-

tion chamber 193 and a delivery chamber 194, which each extend over an angle of almost 180° as may best be seen in FIGURE 20. The chambers 193 and 194 communicate with passages 195 and 196 extending through the housing 191 in a direction parallel to the axes of rotation of the rotary systems.

The first rotary system includes the shackle 185 and the pin 187 thereof and is rotatably mounted in the shell part 192b as shown in FIGURE 21 by means of the shaft 186. The shaft 186 is mounted for rotation about an axis 197 in a needle bearing 193a. A gland 193b is provided, which forms a liquid-tight seal between the shaft 186 and the housing. Since the shaft mounting and sealing arrangements do not form part of the present invention, they will not be further described.

The cylinder block 190 rotates in the housing 191 in the direction of the arrow 199 (FIGURE 23) and about an axis of rotation 200 which is eccentric to the axis 197. The rotation of the cylinder block 190 is caused by the reciprocating piston 188; the motion of the piston 188 will be understood from the description given with reference to FIGURES 1 and 2. The second rotary system operates as a pump to take liquid from a suction chamber 193 and deliver it to a delivery chamber 194, these chambers being formed in the housing 191.

As already explained, the pump delivery performance may be regulated by turning the partitions 301 and 302 (FIGURE 20) which separate the suction chamber 193 from the delivery chamber 194, out of the plane which is defined by the two axes of rotation 197 and 200. This is done by turning the housing 191 in the enclosing shell part 192a by means of the ring gear 303 and a rack 304 in the manner apparent from FIGURES 21 to 24. Suction and delivery are thereby reduced inasmuch as the reciprocating piston 188 no longer delivers the liquid conveyed into the delivery chamber 194 over its full delivery range, but partially also into the suction chamber 193. The same applies in reverse to the suction stroke. The turning of the housing 191 also angularly displaces the passages 195 and 196 which connect the chambers 193 and 194 to the suction and delivery pipes 309, 307 respectively. The bottom of the enclosing shell part 192a is therefore formed (in the manner shown in FIGURE 25) with a duct 306 communicating with the delivery pipe 307 and extending over an arc of 90°; a collector duct 308 is formed in the base of the part 192a, opposite the duct 306.

I claim:

1. A piston pump comprising a pump body, a cylinder block mounted for rotation within the pump body about an axis and defining a plurality of parallel bores extending transversely to said axis, a piston reciprocably mounted in each of said bores, the pump body defining with the cylinder block, an intake chamber and a delivery chamber for each of said bores, both chambers extending over the major portion of a 180° arc centered on said axis, guide members one at either end of the cylinder block and mounted for rotation within the pump body about a second axis parallel to and spaced from the first-mentioned axis, said guide members providing parallel tracks extending transversely to said second-mentioned axis, a slide reciprocably mounted in each track, and an elongated resilient coupler extending parallel to said axes and interconnecting said slides and said pistons for rotation as a unit in an orbital path by reason of a torque transmitted through said coupler.

2. A piston pump as claimed in claim 1, wherein said coupler is in the form of a bar of rectangular cross-section extending through holes of similar cross-section in the slides.

3. A piston pump as claimed in claim 1, wherein the coupler is a rectangular-section member of composite construction consisting of a pair of bar-like elements sandwiching a resilient layer urging said elements apart.

4. A piston pump as claimed in claim 1, further comprising means to apply a drive torque to at least one of said guide members.

5. A piston pump as claimed in claim 1, wherein each guide member is in the form of a disc mounted in a cylindrical recess in the pump body.

6. A piston pump as claimed in claim 1, wherein the pump body comprises a block with a cylindrical recess therein and defining intake and outlet ducts for each of said intake and delivery chambers, said ducts leading to said recess, and a sleeve provided in said recess and having an eccentric bore receiving and rotatably mounting said cylinder block, said sleeve being formed with through-slots in its wall to provide said intake and delivery chambers.

7. A piston pump as claimed in claim 1, wherein the pump body comprises a block with a cylindrical recess therein and a sleeve provided in said recess and having an eccentric bore receiving and rotatably mounting the cylinder block, each guide member being in the form of a disc received and rotatably mounted in the recess in the block with one at each end of the sleeve.

8. A piston pump as claimed in claim 1, wherein said guide members define shallow rectangular-section tracks and said slides being plate-like elements having a cross-section similar to that of the tracks.

9. A piston pump as claimed in claim 1, wherein said slides are plate-like elements of rectangular cross-section and the tracks therefor in said guide elements are of similar cross-section, and said cylinder block defines at least one end of track of rectangular cross-section extending transversely of said first-mentioned axis and reciprocably mounting a further plate-like element, said coupler being in the form of a bar of rectangular cross-section extending snugly through holes of similar cross-section in all said plate-like elements and through cylindrical holes in the pistons.

10. A piston pump as claimed in claim 9, wherein the corners of said coupler bar are rounded.

11. A piston pump comprising a pump body; a cylinder block mounted for rotation within the pump body about an axis and defining a plurality of parallel bores extending transversely to said axis and at least at one end, a rectangular section track extending parallel to said bores; a piston reciprocably mounted in each of said bores; the pump body defining with the cylinder block an intake chamber and a delivery chamber for each of said bores; guide members one at either end of the cylinder block and mounted for rotation within the pump body about a second axis parallel to and spaced from the first-mentioned axis, said members defining parallel rectangular-section tracks extending transversely to said second-mentioned axis; means to apply a driving torque to at least one of said guide members; a flat rectangular slide reciprocably mounted in each said track of the cylinder block and guide members; said slides having rectangular holes therein, and said pistons having circular holes therein; and a straight resilient rectangular coupler bar extending parallel to said axes through the holes in the slides and in the pistons to maintain the slides in the guide members at a 90° orientation to the pistons and to reciprocate the pistons in their bores, upon rotation of said driven guide members.

12. A piston pump as claimed in claim 11, wherein the coupler bar is of composite construction consisting of a pair of bar-like elements sandwiching a resilient layer to urge said bar-like elements into firm engagement with opposite sides of said holes.

13. A piston pump for liquids, comprising a pump body, a cylinder block mounted for rotation within the pump body about an axis and defining at least three parallel bores extending transversely to said axis, a piston reciprocable in each of said bores, the pump body with the cylinder block defining an intake and a delivery chamber for each of said bores, each piston in its respective bore and with its respective intake and discharge chamber constituting an elementary pump stage, at least one guide member mounted for rotation within the pump body

15 around a second axis parallel to and spaced from the first of said guide members and providing a track extending transversely to the second-mentioned axis, a guide element reciprocable along said track, a torque-transmitting coupler extending parallel to said axes and interconnecting said guide element and pistons for rotation in an orbital path with a fixed angular distance therebetween, a main inlet and a main outlet for said pump, an intermediate container duct means interconnecting the first of said elementary pump stages to the inlet and to the intermediate container and a second of said elementary pump stages

20 from the intermediate container to the outlet, a collector space arranged to receive leakage from the pump stages, and duct means interconnecting the third of said elementary pump stages and said intermediate container.

30 14. A piston pump as claimed in claim 13, wherein the outlet is connected to the intermediate container through a first pressure relief valve, the intermediate container being connected to the inlet through a second pressure relief valve, said valves being set for predetermined pressures with the first valve being greater than the second valve.

35 15. A piston pump as claimed in claim 13, wherein the collector space is disposed at a level above the pump stages and is vented to atmosphere through a capillary tube.

16. A piston pump as claimed in claim 13, wherein the intermediate container is annular and surrounds the pump body.

45 17. A piston pump as claimed in claim 13, wherein the intermediate container is annular and surrounds the pump body and an annular inlet chamber also surrounds said body and is divided by an annular filter interposed between the inlet which is on one side of the filter and the first-mentioned pump stage.

18. A piston pump as claimed in claim 13, wherein the coupler is a bar of rectangular section extending through holes of similar sections in the slides and pistons.

50 19. A piston pump as claimed in claim 18, wherein the pistons have central portions of reduced thickness in the direction in which the coupler extends.
